US0D1113708S

(12) **United States Design Patent** (10) **Patent No.:** **US D1,113,708 S**
(45) **Date of Patent:** **** Feb. 17, 2026**

(54) **CHARGING STATION**

(71) Applicant: **Apple Inc.**, Cupertino, CA (US)

(72) Inventors: **Moenish Mottana**, Torrance, CA (US);
Peter Riering-Czekalla, Oakland, CA (US);
Paer Saangloef, Los Angeles, CA (US);
Oliver Seil, Long Beach, CA (US);
Mitchell Suckle, Long Beach, CA (US);
Robert Tang, San Gabriel, CA (US);
Andrew T. Windler, Playa Del Rey, CA (US)

(73) Assignee: **Apple Inc.**, Cupertino, CA (US)

(**) Term: **15 Years**

(21) Appl. No.: **29/969,324**

(22) Filed: **Oct. 22, 2024**

Related U.S. Application Data

(63) Continuation of application No. 29/893,825, filed on Jun. 2, 2023, now Pat. No. Des. 1,057,652.

(57) **CLAIM**

The ornamental design for a charging station as shown and described.

DESCRIPTION

FIG. 1 is a perspective view of a charging station showing the claimed design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the charging station which form no part of the claimed design.

1 Claim, 8 Drawing Sheets
